MEANS FOR SEPARATING FLUID-TAR AND
SLUDGE FROM HOT NEWLY MADE WATER
GASCharles H. Printz, Cleveland, Ohio, assignor to
The Gas Machinery Company, Cleveland, Ohio,
a corporation of Ohio

Application April 24, 1937, Serial No. 138,865

2 Claims. (Cl. 261—7)

My invention relates to seals for water gas sets, and particularly relates to improvements in the casings or housings for the liquor forming the seal, commonly known also as "seal separators" and "wash boxes". As is well known, these seals are primarily designed to prevent movement of gas in the wrong direction and are usually plain boxes or casings containing suitable liquor beneath the surface of which the 5 made gas from the gas set is conducted from the gas offtake of the set, the gas passing through the liquor and out from the seal casing and being conducted into storage, or to place of consumption, or any other suitable and desired place. 10 These seal casings usually have flat bottoms, and the fluid tar and heavy sludge carried in by the gas settle by gravity and collect upon the flat bottoms, and thus are separated from the gas 15 passing through the seal casing. When heavy oil 20 is used for enrichment of the water gas made in the set, and even when gas oil is used for such enrichment together with bituminous coal in the generator, great difficulty is encountered in the use of the known forms of seals because of the 25 formation of tar and liquor emulsion in the seal. The separating liquor is agitated by the bubbling 30 gas and this agitation results in the formation of tar emulsions, if the separated tar and sludge are not promptly removed from the sphere of the 35 agitated liquor. The separated tar must be de-emulsified before the tar is marketable, and this de-emulsification involves considerable additional equipment and expense. It is designed by my improved casing for liquid-seals of gas sets 40 to obviate the formation of tar and liquor emulsion.

The annexed drawing and the following description set forth in detail certain means illustrating my improvements, such means constituting, however, only one of the many forms in which the principle of my invention may be embodied.

The drawing is a vertical longitudinal section, partially in elevation, of my improved casing for 45 liquid-seals of water gas sets, including some accessory inlets, outlets, drain tank, etc.

Referring to the annexed drawing, a casing 1 is provided with an upper gas inlet 2 and a gas outlet 3 and, in use, is filled with hot liquor 4 to 50 a level above the bottom of the inlet 2, to form a seal in which fluid tar and heavy sludge are separated from the gas as it passes through the liquor 4 from the inlet 2 to the outlet 3. In the form of casing 1 shown, I provide a hopper-shaped bottom 5 therefor. The fluid tar and

heavy sludge are separated from the gas as the latter bubbles through the seal liquor and settle toward the bottom of the casing 1, the heavy sludge sliding on the hopper bottom 5 toward a bottom outlet 6 therefrom. This bottom outlet 5 is a throat-like member controlled by a valve 7 and opens into the top of an auxiliary casing 8 which also has a hopper-shaped bottom 9 and a discharge spout 10 therefrom controlled by a valve 11. Adjacent the top of the hopper bottom 10 10 9 is a drain pipe 12. The casing 8 functions as a displacement tank for the fluid tar and heavy sludge which settle thereinto through the throat-like pipe 6 and collect upon the bottom of the tank 8, the heavy sludge 13 collecting at the extreme bottom and the fluid tar 14 forming a layer thereabove. The fluid tar is drained off through the pipe 12 and the heavy sludge is drained off through the discharge nozzle 10. The displacement tank 8 forms a quiescent chamber 15 in which there is no emulsifying of the tar and liquor, so that the fluid tar and heavy sludge are available for the market, in the condition in which they are drained from the tank 8, without the necessity of de-emulsification. It will be 20 observed, of course, that the displacement tank 8 is also full of hot liquor 4, being originally filled at the same time as the casing 1. Liquor may be made available for refilling the displacement tank 8, as hereinafter explained, through a controlled liquor inlet 15, the top of the tank 8 being connected with the normal liquor inlet 16 by a pipe 17, the spilling of the liquor from the pipe 17 into the inlet 16 indicating when the tank 8 25 is full. A controlled steam connection 22 to the displacement tank 8 permits heating of the liquor 30 in the tank 8 as desired.

The normal outlet from the seal proper 1 is indicated by the number "18" and it is connected with the normal drain tank 19 by a pipe connection 20, a pipe connection 21 tapping the bottom of the drain tank 19 and serving as a tar drain 35 from the tank 19.

During the operation of the water gas set, the separation of the light and heavy tar from the 45 hot made-gas is effected in the seal, due to the contact of said gas with the seal liquor 4, which light and heavy tar settle downwardly through the liquor 4 and pass through the throat-like member 6 and collect in the bottom of the displacement tank 8. During this operation valve 7 is open, and discharge spout 10 and pipes 12 and 15 are closed. When it is desired to remove the fluid tar and heavy sludge from the tank 8, valve 1 is closed and pipe 12 is first opened to 50 55

drain off the fluid tar. After this drainage is effected, valve 11 is opened and the heavy sludge is discharged through spout 10. Then, to refill the tank 8, outlets 10 and 12 are closed and inlet 5 15 is opened and hot liquor fed into the tank 8 until it spills over into the inlet 16 from the pipe 17. Then valve 7 is opened and the process is repeated.

10 Drainage of the fluid tar and heavy sludge from the tank 8 is effected at such suitable intervals as will obviate the collection of so much heavy sludge as would cover the inlet to the fluid-tar drain 12. However, when the generator of the water gas set is cleaned as often as every 15 other day, the valve 7 can be closed and the line 12 opened and the tar and liquor drained from the displacement tank 8 directly into suitable tar and liquor storage, a pump being utilized for this purpose if necessary. Then the valve 11 is 20 opened, and the heavy sludge discharged into any suitable receptacle.

25 The use of the improvements which have been described and which are shown in the accompanying drawing has resulted in entire freedom from tar and liquor emulsion troubles, even with the use of heavy oil in the water gas set for gas enrichment purposes, and even with the use of gas oil for enrichment together with bituminous coal in the generator. Also, the separated tar obtained by the use of the described improvements 30 contains so small a percentage of moisture that very slight, if any, dehydration of the tar is required.

35 What I claim is:

35 1. Means for separating fluid-tar and sludge from hot newly-made water gas comprising a seal provided with a liquor inlet, said seal having in its upper part a gas inlet and a gas outlet, and forming a gas-bubbling chamber when the 40 seal is filled with liquor to a level above the gas inlet, the seal having a hopper-shaped bottom provided with a bottom discharge opening and

5 forming a fluid-tar and sludge settling compartment, means for maintaining a liquor level in said seal above the gas inlet and below the gas outlet, a fluid-tar and sludge displacement tank below the seal, means forming a constricted passage-way between the discharge opening at the bottom of the hopper-shaped portion of said seal and said tank, means for controlling said passage-way, the tank having a hopper-shaped bottom formed at its bottom with a controlled sludge 10 drain, said tank also having a fluid-tar side drain substantially higher than its sludge drain, controlled means for admitting liquor to the tank other than through said constricted passage-way, and means forming a fluid conduit between the 15 top of the tank and the liquor inlet of the seal.

2. Means for separating fluid-tar and sludge from hot newly-made water gas comprising a seal separator having in its upper part a liquor inlet, a gas inlet, a gas outlet, and means for 20 maintaining a liquor level above the gas inlet and below the gas outlet, the lower part of the separator being organized into the following elements: a hopper-shaped top portion having a 25 bottom discharge opening, a throat-like member adjacently below said opening and into which the hopper-shaped portion feeds, a displacement tank adjacently below said throat-like member and into which the latter discharges, a valve control for said throat-like member, the lower end of the displacement tank being hopper-shaped, a controlled sludge drain tapping the tank at the bottom of said hopper-shaped lower end, a controlled fluid-tar drain tapping the tank in an area substantially higher than the bottom of 30 said hopper-shaped lower end, and controlled means for admitting liquor to said tank from a source other than said hopper-shaped top portion, said controlled means including an inlet to and an overflow from said tank. 40
